WIRE COILING AND INTERWEAVING
MECHANISMParmen F. Frost, Mount Vernon, N. Y., and
John C. Anderson, Keyport, N. J.

Application February 18, 1936, Serial No. 64,426

10 Claims. (Cl. 140—8)

This invention relates to improvements in coiling mechanism used in making and interweaving coiled wires in the manufacture of wire netting and more particularly to improvements in coiling mechanism for making and interweaving coiled wire netting in which the coils are flattened.

- 10 Heretofore many types of mechanisms have been used for the manufacture of flattened coiled wire netting, but all of such mechanisms have been so constructed as to present definite limitations as to the angularity of the coils, etc. In other words, the mechanisms have been so constructed that the maximum angle at which the wires can be coiled has been approximately 45°.
- 15 When attempts have been made to increase the angle to say 60°, the resultant friction set up in the mechanism has been so great as to practically prevent operation of the mechanism on any but very small wire.
- 20 An object of the present invention is to provide mechanism for coiling and interweaving wire into netting of such construction that the angle at which the wire is coiled can be considerably increased beyond that possible in prior practice.

- 25 Another object of the invention is to provide in mechanism of the foregoing character, an auxiliary member moving in synchronism with the customary mandrel for aiding said mandrel in advancing wire through the die.
- 30 A further object of the invention is to provide means for facilitating the introduction of wire into a die groove of relatively wide angularity.

- 35 Another additional object of the invention is to provide a forming die in which the groove is of a relatively wide angularity throughout the major portion of the length thereof and is of a different angularity at the entrance thereof, to facilitate introduction of the wire into the forming groove.

- 40 A still further object of the invention is to provide a mandrel for use in connection with a forming die having a forming groove of relatively wide angularity, such mandrel having a portion thereof twisted adjacent the entry end of the groove to facilitate the introduction of wire thereto.

- 45 The mechanism embodied in the preferred form of the present invention comprises a spirally grooved die held in stationary position by some suitable clamp mechanism at the respective ends thereof; a mandrel rotatable within the die; and a sleeve encircling the major portion of the die and arranged to rotate in synchronism with the mandrel. The mandrel is in the form substantially of a flat blade; and the sleeve is provided with diametrically opposite grooves extending longitudinally thereof in alignment with the edges of the mandrel. Suitable mechanism is provided for rotating the mandrel and the sleeve in synchronism. The die preferably has a cylindrical wall of slightly less thickness than the diameter of

the wire to be coiled. Due to the relative alignment of the edges of the mandrel and the grooves in the rotating sleeve, that portion of the wire extending through the groove of the die can fit in the grooves of the sleeve, and since the mandrel and sleeve are rotated in synchronism, it follows that the rotating grooves materially aid the mandrel in forcing the wire through the die. As the result of this cooperation between the mandrel and the sleeve, it is possible to increase the angularity of the spiral groove in the die so that the coiled wire has the turns thereof at a relatively great angle. When the coiled wire is interwoven, it follows that the distance between engaged loops in one plane is considerably greater than the distance between the engaged loops in the other plane. To facilitate the introduction of the wire into the spiral groove of the desired angularity, either one of two expedients can be used. In one form of the invention the die has the major portion thereof at the desired wide angle, while the groove at the end of introduction of the wire is of a different angularity more in keeping with that ordinarily used in prior practice. This modified angularity of the groove exists for such a distance of the groove as to introduce a loop of the wire into a groove in the sleeve, after which the die groove extends at the desired angularity. In another form of the invention the mandrel is provided with a twisted portion positioned at the entry end of the die, which twisted portion serves the same function as the modified angularity of die groove.

Other features, objects and advantages of the invention will become apparent by reference to the following detailed description thereof read in the light of the accompanying drawing, wherein

Fig. 1 is a side elevation, partially in section, of mechanism embodying the invention.

Fig. 2 is an enlarged vertical section taken substantially on the line 2—2 of Fig. 1.

Fig. 3 is an enlarged vertical section taken substantially on the line 3—3 of Fig. 1.

Fig. 4 is a plan view of a twisted mandrel used in one embodiment of the invention; and

Fig. 5 is an enlarged fragmentary showing of a die used in the invention.

Referring now to the drawing, 10 indicates a cylindrical or tubular die member which is provided with a spiral groove 11 extending completely lengthwise thereof and cut completely through the wall of the die. The respective ends of the die 10 are clamped in supports 12 and 14 which may extend upwardly from a suitable base 50 15. Surrounding rings 12' and 14' are secured to the die by set screws. The supports 12 and 14 are in the form of split rings which can be drawn together by a suitable nut and bolt arrangement 16 passing through upstanding ears 60

17 to clamp the rings 12' and 14' and to thereby lock the die against any movement. Any other suitable locking arrangement can be used for restraining the die from any movement.

5 Fitting around the die 10 between the supports 12 and 14 is a tubular sleeve 20. This sleeve is of such length as to fit closely between the locking rings 12' and 14', yet be capable of rotation about the die. The inner surface of 10 the sleeve 20 is provided with diametrically opposite longitudinally extending grooves 21. The purpose of these grooves will be explained later. Secured to the sleeve is a cog wheel 22 around which passes a chain belt 24, also passing over 15 a similar wheel 25 on a countershaft 26.

Spaced from the support 12 is a head 30 within 20 which is rotatably mounted a power shaft 31 in axial alignment with the die 10. Some suitable source of power may be utilized for rotating the shaft 31. This shaft has one end thereof split 25 for the reception of one end of a flat blade-like mandrel 32, which mandrel can be locked in place by means of a screw 34 in the customary fashion. The end of the shaft 31 has a cog 30 wheel 35 thereon over which passes a chain belt 36, also passing over a similar cog wheel 37 on the countershaft 36. By this arrangement it will be evident that when the shaft 31 is rotated to rotate the mandrel 32, which extends completely 35 through and beyond the die 10, the sleeve 20 will be rotated in synchronism with the mandrel.

In the assembly of the component parts of the mechanism, the blade 32 is so introduced into the die and registered relative to the sleeve 29 35 that the grooves 21 in the sleeve are in exact alignment with the two edges 38 of the mandrel. The wall thickness of the tubular die 10 depends on the size of the wire 50 to be coiled by the mechanism. Preferably, the thickness of the 40 wall of the die 10 is slightly less than the diameter of the wire 50 so that when this wire is bent around the mandrel 32, an edge of the wire will extend through the groove 11.

By reference to the drawing, it will be seen 45 that the groove 11 is so formed as to extend at an angle of substantially 60° relative to a plane transverse of the die or at an angle of 30° relative to a plane extending axially of the die. When efforts have been made to use a groove of 50 such angularity prior to the present invention, it has been found that the friction set up due to this angularity has been so great as to prevent the passage along the groove of any wire, except very fine wire. It should be noted, however, that 55 end portion 51 of the groove extends substantially at an angle of 45° to either the cross, axial or axial plane of the die. The purpose of this change in angularity of the groove is to facilitate the introduction of the wire into the forming groove, since the wire will pass through a groove more readily when the groove more nearly approaches a direction cross-axially of the die.

When the wire 50, under tension due to the 60 customary tension device 52, is fed over the mandrel 32 and introduced into a portion 51 of the groove and the mandrel is then rotated, the wire is advanced through the groove of the forming die. This variation in angularity in the groove is particularly useful in mechanisms wherein 65 the mandrel is a substantially flat straight blade. In order that the wire may be advanced through the forming die more readily, use is made in the present invention of the rotating sleeve 20 having the opposite grooves 21 therein. Since these 70 grooves are in alignment with the edges of the

mandrel, and since, as before pointed out, the wire looped around the edges of the mandrel is of such size as to extend through the groove, the loops extend into the grooves 21 as shown clearly in Fig. 2. Thus, in addition to the normal advancing action of the mandrel itself, a cumulative advancing action is afforded by the sleeve which rotates in synchronism with the mandrel. Due to this coaction between the mandrel and the grooved sleeve, the friction which is set up 10 is substantially overcome so that the wire advances as readily through the groove of the angularity shown as it will through a groove of substantially 45° or less angularity.

The shape of the wire emerging from the forming die is shown clearly in Fig. 1, wherein it will be noted that the angle between two expanses of the wire is substantially 120°. When a wire so coiled has been woven into netting, the loops of the netting will be found to be substantially 20 diamond shaped, being made up of two 120° angles and two 60° angles. Such netting possesses many advantages over the ordinary square mesh netting heretofore manufactured, in that the netting can be used more advantageously for 25 fence purposes due to the restriction of the horizontal measurements of the mesh (it being understood that the wire is woven from top to bottom of what is intended to be fence netting). Since this horizontal measurement can be materially 30 reduced, it follows that a fence made of the wire affords less chances for foot-holds than the square mesh. Furthermore, with a given horizontal measurement of loops a saving in wire can be effected by utilizing the wide angularity of 35 the forming die groove.

In the event it is undesirable to have the groove 40 11 of different angularities, a mandrel similar to that shown in Fig. 4 can be used. When this mandrel is used the groove may be of the same 45 angularity throughout the length of the die. The mandrel 60 of Fig. 4 is provided with a twisted portion 61 which can be so positioned that approximately half of the twisted portion extends beyond the entry end of the die. Thus when a 50 wire is fed over this mandrel and introduced into the groove, the looping of the wire is accelerated at the point of entry so that the wire assumes, in effect, the shape it assumes in a groove of 45° angularity. The entrance of the wire into the 55 groove is thereby facilitated.

While the mandrel has been described as being a flat blade with the sleeve having grooves therein extending longitudinally thereof in register with the edges of the mandrel, at the same time it 60 is to be understood that the blade can be slightly twisted in the expanses thereof within the die, and that the sleeve grooves will be correspondingly shaped. The purpose of such twisting within the die is to eliminate any actual twisting of the coils of wire which would prevent the netting from being substantially flat. When the expasne of the mandrel within the die is straight, then the expasne of mandrel beyond the end of the die can be twisted in the usual fashion to 65 serve the same purposes.

The use of the rotating sleeve and the advantages inherent therein have been set forth particularly in connection with dies, the groove of which has an angularity in excess of 45°. It is 70 to be understood, however, that the rotating sleeve will facilitate the advancement of wires through a grooved die in which the groove has any desired angularity. Furthermore, while the sleeve has been shown as being of a rotary character 75

with opposite grooves in alignment with the edges of the mandrel, it is also contemplated that the sleeve could have an uninterrupted inner surface, and could be stationary relative to the die. When 5 the sleeve is stationary it is possible to use a die having a groove of an angularity somewhat in excess of 45° provided some arrangement is used for facilitating the introduction of the wire into the die. Either one of the forms of devices 10 described hereinbefore will serve this purpose, that is, either the change in angularity at the entrance end of the die, or the mandrel having a twist therein at the entrance end of the die, will serve to cause the proper introduction of the wire into 15 the portion of the groove of angularity in excess of 45°. When the sleeve is stationary, it is essential that the die have a wall thickness slightly less than the diameter of the wire being looped. Moreover, the invention is adaptable for use in 20 arrangements wherein two strands of wire are simultaneously advanced through the same die, the only requirement being that the grooves be properly arranged for such purpose.

From the foregoing it will be seen that the present 25 invention provides novel mechanism for producing looped wire netting in which the openings are of substantially diamond-shape. Such wire netting in addition to the uses and advantages pointed out hereinbefore also has pleasing ornamental effects. It is to be understood that the invention is not to be limited to the illustrated 30 embodiments but is to be limited only by the scope of the following claims.

We claim:

35 1. In mechanism for producing looped wire netting, a tubular die having a spiral groove through the wall thereof and extending longitudinally thereof with at least the major portion thereof at a pitch in excess of 45°, a mandrel extending 40 through said die, a tubular sleeve member fitting around said die, and means at the entrance end of said die for facilitating introduction of a wire into the groove of the die.

2. In mechanism for producing looped wire netting, a tubular die having a spiral groove through 45 the wall thereof and extending longitudinally thereof, a portion of the groove at the entrance end of the die being at a different pitch from that of the major portion thereof to facilitate 50 entry of a wire into the major portion, a mandrel extending through said die, and a tubular sleeve member fitting around said die.

3. In mechanism for producing looped wire netting, a tubular die having a spiral groove through 55 the wall thereof and extending longitudinally thereof with at least the major portion thereof at a pitch in excess of 45°, a mandrel extending through said die, and a tubular sleeve member fitting around said die, said mandrel having a portion thereof at the entrance end of the die 60 twisted to facilitate the introduction of a wire into the groove of the die.

4. In mechanism for producing looped wire netting, a tubular die having a spiral groove 65 through the wall thereof and extending longitudinally thereof, a mandrel extending through said die, a tubular sleeve member fitting around said die and being provided with longitudinally extending grooves on the inner surface thereof, and means for rotating said mandrel and sleeve 70 in synchronism.

5. In mechanism for producing looped wire netting, a tubular die having a groove through the wall thereof and extending spirally longitudinally thereof, a substantially flat blade-like mandrel extending through said die, a tubular sleeve 5 surrounding the major portion of said die, the inner surface of said sleeve being provided with longitudinal grooves aligned with the edges of said mandrel, and means for rotating said mandrel and said sleeve in synchronism. 10

6. In mechanism for producing looped wire netting, a tubular die having a groove through the wall thereof and extending spirally longitudinally thereof, said groove having an angularity relative to a plane cross-axially of said die greater than 45° throughout the major portion of the length thereof, and having an angularity not greater than 45° at one end thereof, a substantially flat blade-like mandrel extending through said die, a tubular sleeve surrounding the major 20 portion of said die, the inner surface of said sleeve being provided with grooves aligned with the edges of said mandrel, and means for rotating said mandrel and said sleeve in synchronism.

7. In mechanism for producing looped wire netting, a tubular die having a groove through the wall thereof and extending spirally longitudinally thereof, said groove having an angularity relative to a cross-axial plane of said die in excess of 45°, a substantially flat blade-like mandrel extending through said die, said mandrel having a twisted portion adjacent the entry end of said die, a tubular sleeve surrounding the major portion of said die, the inner surface of said sleeve being provided with grooves in alignment with the edges of the mandrel, and means for rotating said mandrel and sleeve in synchronism. 30

8. In mechanism for producing looped wire netting, a tubular die having a spiral groove 40 through the wall thereof and extending longitudinally thereof with at least the major portion at a pitch in excess of 45°, a mandrel extending through said die, a tubular sleeve member fitting around said die, and means for rotating said 45 mandrel and sleeve in synchronism.

9. In mechanism for producing looped wire netting, a tubular die having a groove through the wall thereof and extending spirally longitudinally thereof with at least the major portion 50 of said die at a pitch in excess of 45°, a substantially flat blade-like mandrel extending through said die, a tubular sleeve surrounding the major portion of said die, the inner surface of said sleeve being provided with longitudinal grooves aligned 55 with the edges of said mandrel, and means for rotating said mandrel and said sleeve in synchronism.

10. In mechanism for producing looped wire netting, a tubular die having a spiral groove 60 through the wall thereof and extending longitudinally thereof with at least the major portion thereof at a pitch in excess of 45°, a mandrel extending through said die, a tubular sleeve member fitting around said die and being provided with longitudinally extending grooves on the inner surface thereof, and means for rotating said mandrel and sleeve in synchronism. 65
